[57] CLAIM

The ornamental design for a wide angle strobe light for
emergency vehicles or the like, substantially as shown
and described.

DESCRIPTION

FIG. 1 is a top view of a wide angle strobe light for
emergency vehicles or the like in accordance with my
novel design, the light appearing the same from the
bottom;

FIG. 2 is a front elevational view thereof;

FIG. 3 is a rear elevational view thereof; and

FIG. 4 is a side elevational view thereof, the light ap-
pearing the same from the opposite side.

FIG. 1

FIG. 2

FIG. 3

FIG. 4
